PADLOCK

Frank E. Raymond, Stamford, Conn., assignor to
The Yale & Towne Manufacturing Company,
Stamford, Conn., a corporation of Connecticut

Application March 2, 1937, Serial No. 128,609

11 Claims. (Cl. 70—38)

This invention relates to a padlock of the type in which the shackle is locked by a spring.

In padlocks of this type, the spring usually has one or more legs which lock into notches on the padlock shackle, the legs being spread apart by a key so as to be moved out of the notches in the shackle so that the shackle may be projected out of the padlock casing.

It is necessary in a padlock of this type to provide means for limiting the movement of the shackle out of the casing, also to provide means for preventing reinsertion of the shackle in a particular rotated position which will allow locking of the shackle with one of its legs not in the padlock casing.

My invention contributes to the art a novel and extremely simple means for limiting the movement of the shackle out of the casing and for preventing the shackle from being locked when disaligned relatively to the casing. While I shall describe a specific form of my invention, it should be understood that my contribution is basic, and that I should not be limited to the particular features of the construction herein shown and described.

I shall now refer to the drawing wherein Fig. 1 is a section of my lock taken along lines 1—1 of Fig. 2, Fig. 2 being an elevation of the padlock with one half of the casing removed. Fig. 3 is a section along the lines 3—3 of Fig. 2. Figs. 4 and 5 are drawn along the same lines as Fig. 3 and show the parts in different positions. Fig. 6 is a side view of the lock of Fig. 2 with part of the front half of the casing shown replaced, and with the shackle shown partially out of the casing and in a released position.

Referring now more particularly to the drawing, my padlock casing is formed of two parts 11 and 12, probably best shown in Fig. 1, held together by four rivets 13 in a manner well understood by those skilled in the art. A U spring 14 is mounted transversely of the casing, as is probably best shown in Fig. 1, and has a locking leg 15 and a limiting leg 16, the function of which will be described later. The locking leg 15 fits into the notch 15a of a shackle 17 which has a nose 18 fitting into a chamber 19 formed between the two halves 11 and 12 of the padlock casing.

The shackle 17 extends downwardly and terminates in a shouldered portion 20 with which cooperates a spring 21 tending to move the shackle upwardly from its position of Fig. 2 to its position of Figs. 4 and 6, when the shackle is released by movement of the locking leg 15 of the spring 14.

For operating the locking leg 15 of spring 14, my casing has mounted a key guideway 22 having a series of notches 23, any one of which may house a ward 24 which cooperates with a key 25. The key 25 is designed to escape the one or more wards 24 which may be used so that it may be rotated from its full line position of Fig. 1 to the dotted line position of Fig. 1, and in so doing, move the leg 15 of spring 14 from its full line position in Fig. 1 to its dotted line position in Fig. 1 and out of the notch 15a of the shackle 17.

The shackle will then be propelled by spring 21 from its position of Fig. 3 to its position of Figs. 4 and 6. The leg 16 of the spring 14 is bent at 26 so that the key 25, in rotating, will not move the said leg 16. Therefore, leg 16 will be in a position to cooperate with the shouldered portion 20 of the shackle 17, as is probably best shown in Fig. 4, for limiting the movement of the shackle 17 out of the padlock casing.

Referring now to Figs. 3, 4 and 5, it will be noticed that the leg 16 of the spring 14 is offset relatively to the leg 15, the offset being in the direction of the movement of the shackle 17 in and out of the padlock casing. This offset relationship is particularly designed to prevent the reinsertion of the shackle 17 into the casing in any position other than that shown in Figs. 3 and 4. It will be noted that if the shackle is moved downwardly from its position of Fig. 4, the notch 15a will come opposite the spring 15, whereupon the spring 15 will drop inwardly into the notch 15a and lock the shackle as shown in Fig. 3.

If the shackle 17 in Fig. 4 be rotated, however, so as to bring its nose 18 to the position of Fig. 5, then the shoulder 27 of the shackle 17 will be imposed over leg 16 of the spring 14. In this position of the parts, it will be impossible to move the shackle downwardly into the casing. This, of course, prevents the shackle from being locked by the leg 16 of the spring 14 through entry of the spring into the notch 15a. In this way, the leg 16 of the spring 14, in addition to its function of limiting the ejection of the shackle from the padlock casing, also controls the reinsertion of the shackle into the casing, and prevents the locking of the shackle in any position but a predetermined position.

It is readily appreciated that if the relation of the parts were not as herein shown, the shackle could be rotated from the position of Fig. 4 to the position of Fig. 5 and then pushed downwardly, so that the spring leg 16 would thereafter lock the shackle in the casing while the nose 18 of the shackle was out of the chamber 19. This would

require a reopening of the lock, and in case the key were not available, the padlock would be rendered temporarily useless.

Those skilled in the art will readily appreciate the number of advantages inherent in my structure, and will readily appreciate the simple manner in which I obtain the results required.

I now claim:

1. In a padlock of the class described, a padlock casing, a shackle, a spring for locking said shackle having a pair of legs, a portion of said shackle cooperating with one of said legs when said shackle is in locked position in said casing whereby said leg retains said shackle in said locked position, said spring leg being movable by key operation out of cooperation with said shackle to permit movement of said shackle out of said padlock casing, and means on said shackle cooperable with the other leg of said spring as said shackle moves outwardly of said casing whereby to limit the movement of the shackle out of said padlock casing.

2. In a padlock of the class described, a padlock casing, a shackle, a U spring for locking said shackle having a pair of substantially parallel legs, a portion of said shackle cooperating with one of said legs when said shackle is in locked position whereby said leg retains said shackle in said locked position, said spring leg being movable by key operation out of cooperation with said shackle to permit movement of said shackle out of said padlock casing, and means on said shackle cooperable with the other leg of said spring as said shackle moves outwardly of said casing whereby to limit the movement of the shackle out of said padlock casing.

3. In a padlock of the class described, a padlock casing, a shackle, a spring for locking said shackle having a pair of legs, a portion of said shackle cooperating with one of said legs when said shackle is in locked position whereby said leg restrains said shackle in said locked position, said spring leg cooperating with said shackle being movable by key operation to release said shackle for movement out of said padlock casing while the other spring leg remains fixed, and means on said shackle cooperable with said fixed spring leg as said shackle moves outwardly of said casing to limit the movement of the shackle out of said padlock casing.

4. In a padlock of the class described, a padlock casing, a shackle, a U spring for locking said shackle having a pair of substantially parallel legs, a portion of said shackle cooperating with one of said legs when said shackle is in locked position whereby said leg retains said shackle in said locked position, said spring leg cooperating with the said shackle being movable by key operation to release the shackle for movement out of said padlock casing, the other of said spring legs being deformed to avoid said key operation whereby to remain fixed, and a further portion of said shackle cooperable with said fixed spring leg to limit the movement of the shackle out of said padlock casing.

5. In a padlock of the class described, a padlock casing, a shackle, a spring for locking said shackle having a pair of legs, a portion of said shackle cooperating with one of said legs when said shackle is in locked position whereby said spring leg retains said shackle in said locked position, said spring leg being movable by key operation out of cooperation with said shackle to permit releasing movement of said shackle out of said casing, said shackle being freely rotatable

when partially out of said casing, and means on said shackle cooperating with said other spring leg for preventing movement of said shackle back into locked position until said shackle is rotated to a predetermined aligned position relatively to said casing.

6. In a padlock of the class described, a padlock casing, a shackle having a toe and a heel, a spring for locking said shackle at its heel, a portion of the heel of said shackle cooperating with a portion of said spring when said shackle is in locked position whereby said spring retains said shackle in said locked position, said spring portion being movable by key operation out of cooperation with said shackle heel portion to permit releasing movement of said shackle out of said casing, said shackle being freely rotatable when partially out of said casing, and means on said shackle heel cooperable with another portion of said spring for preventing movement of said shackle back into locked position until said shackle is rotated to a predetermined aligned position relatively to said casing.

7. In a padlock of the class described, a padlock casing, a shackle, a U spring for locking said shackle, a notched portion of said shackle cooperating with one leg of said U spring for locking said shackle in said casing, said spring leg being movable by key action out of the notch in said shackle to permit sliding of said shackle out of said casing while said spring leg bears frictionally on said shackle ready to jump into said notch when said shackle is moved back into said casing, the other leg of said U spring being adapted to rub on the other side of the shackle as said shackle moves in and out of said padlock, said other spring leg being offset in a direction parallel to the shackle movement relatively to said first spring leg, and a surface on said shackle cooperable with said offset spring leg to prevent sliding of said shackle into locked position in said casing until said shackle is properly aligned relatively to said casing and said first spring leg.

8. In a padlock of the class described, a padlock casing, a shackle, a U spring for locking said shackle, a notched portion of said shackle cooperating with one leg of said U spring for locking said shackle in said casing, said spring leg being movable by key action out of the notch in said shackle to permit sliding of said shackle out of said casing while said spring leg bears frictionally on said shackle ready to jump into said notch when said shackle is moved back into said casing, means on said shackle cooperable with the other leg of said U spring for limiting the movement of said shackle out of said casing, said other spring leg being offset in a direction parallel to the shackle movement relatively to said first spring leg, and a surface on said shackle cooperable with said offset spring leg to prevent sliding of said shackle into locked position in said casing until said shackle is properly aligned relatively to said casing and said first spring leg.

9. In a padlock of the class described, a padlock casing, a shackle, a U spring for locking said shackle, a notched portion of said shackle cooperating with one leg of said U spring for locking said shackle in said casing, said spring leg being movable by key action out of the notch in said shackle to permit sliding of said shackle out of said casing while said spring leg bears frictionally on said shackle ready to jump into said notch when said shackle is moved back into said casing, the other leg of said U spring being adapted to rub on the other side of the shackle, the end of

the shackle cooperating with said other spring leg to limit the movement of said shackle out of said casing, the said shackle being rotatable when out of the casing a predetermined distance, and
5 means on said shackle cooperable with said other spring leg to prevent reinsertion of said shackle except when its locking notch is aligned relatively to said first spring leg.

10. In a padlock of the class described, a padlock casing, a shackle, a U spring for locking said shackle, a notched portion of said shackle cooperating with one leg of said U spring for locking said shackle in said casing, said spring leg being movable by key action out of the notch in said shackle to permit sliding of said shackle out of said casing while said spring leg bears frictionally on said shackle ready to jump into said notch when said shackle is moved back into said casing, the other leg of said U spring being adapted to rub on the other side of the shackle as said shackle moves in and out of said padlock, the end of the shackle cooperating with said other spring leg to limit the movement of said shackle out of said casing, the said shackle being rotatable when out 20 of the casing a predetermined distance, said other spring leg being offset in a direction par-

allel to the shackle movement relatively to said first spring leg, and a surface on said shackle cooperable with said offset spring leg to prevent sliding of said shackle into locked position in said casing until said shackle is properly aligned 5 relatively to said casing and said first spring leg.

11. In a padlock of the class described, a padlock casing, a shackle, a U spring having a pair of substantially parallel legs, one of which fits into a locking notch of said shackle for locking 10 said shackle against movement outwardly of said casing, a shouldered portion on said shackle on the side thereof in which said locking notch is formed and below said locking notch, a limiting notch on the side of said shackle opposite said 15 locking notch, the other leg of said spring resting normally in said limiting notch to limit the outward movement of the shackle when it is released by said first leg, said shackle being free for rotation when out of said casing an extent 20 allowed by said other spring leg, said other spring leg cooperating with said shouldered portion to prevent the insertion of the shackle fully into said casing when said shouldered portion is opposite said other spring leg. 25

FRANK E. RAYMOND.
